WINDSHIELD CLEANING SYSTEMErwin C. Horton, Hamburg, N.Y., assignor to
Trico Products Corporation, Buffalo, N.Y.

Continuation of applications Ser. No. 415,544 and Ser. No. 415,619, Mar. 11, 1954. This application July 7, 1958, Ser. No. 748,558

17 Claims. (Cl. 15—250.02)

This invention relates generally to the window cleaning art, and more specifically to a new and useful washing and wiping system particularly adapted for the cleaning of vehicle windshields.

This application is a continuation of applications 415,544 and 415,619 filed March 11, 1954.

Heretofore, a plurality of manual operations were required to institute and complete the windshield washing cycle, specifically, commencing the operation of the washer, starting the wipers, shutting off the washer and stopping the wipers. Apart from the inconvenience to the operator of the vehicle resulting from the manipulation of the various controls, a distinct driving hazard exists due to the distraction of the operator's attention from the road during the washing cycle. The need for a system whereby the washing cycle may be carried out with a minimum amount of attention from the operator is obvious.

Accordingly, it is a primary object of this invention to provide a new and useful vehicle window cleaner wherein in a wiper action is initiated automatically upon initiating a window washing operation, the wipers also being selectively operable independently of the washer.

Another object of this invention is to provide a window cleaning system wherein the wipers are operated at full speed automatically upon actuating the washer.

It is also an object of this invention to provide a window cleaner unit as aforesaid and wherein at the end of the washing action the wipers are automatically restored to the parked or running condition for which the independently operable wiper control is set.

A further object of this invention is to provide a vehicle window cleaning system having the aforesaid characteristics and which is of a relatively simple and inexpensive construction.

A window cleaner system according to the invention is characterized by the provision of a wiper unit including a wiper motor having a control valve movable between off and full running positions, first control means for selectively actuating said control valve to initiate a wiper action, a washer unit, second control means for selectively actuating said washer unit to initiate a washing action, and third control means interconnecting the washer and wiper units and automatically responsive to actuation of the washer unit to move said control valve to a running position for high speed wiper operation during the washing operation, said third control means being operative to move said control valve from its position prior to washer actuation to such running position and back without relative movement in said first control means.

More specifically, a window cleaner system according to the invention is characterized in one form thereof by the provision of a movable wiper motor control valve, a control cable therefor having a wire slidably within a casing and connected at one end to said control valve, the other end of said wire being connected to a first control member for selective actuation of the motor, a washer unit, a second control member for selectively actuating the washer unit, means responsive to actuation of the washer unit and connected to the control cable casing for moving the control cable and the control valve bodily as a unit to place the motor control valve in full running position, and stop means positively precluding movement of the motor

2

control valve beyond its full running position, the means responsive to actuation of the washer unit being of sufficient strength to move the cable bodily as a unit without sufficient power to cause relative movement between the wire and casing thereof.

In another form thereof, a window cleaning system according to the invention is characterized by the provision of means enabling overtravel of the motor control valve, beyond its full running position as determined by the first control means, without restriction of motor speed because of such overtravel.

The foregoing and other objects and advantages of this invention will become clearly evident from the ensuing detailed description thereof, taken together with the accompanying drawing wherein:

FIG. 1 is a somewhat schematic view of one embodiment of a window cleaning system according to this invention installed in place on a vehicle;

FIG. 2 is a schematic layout of the washer responsive wiper control means of the system of FIG. 1, with the motor control valve shown in full running position;

FIG. 3 is a schematic fragmentary detail view similar to FIG. 2 but illustrating the motor control valve in parked position;

FIG. 4 is a view similar to FIG. 3 but illustrating another embodiment of the invention;

FIG. 5 is a schematic layout of still another embodiment of the invention;

FIG. 6 is a fragmentary sectional view through the washer responsive wiper control of FIG. 5;

FIG. 7 is a diagrammatic view of an automotive vehicle equipped with another embodiment of a coordinating system constructed in accordance with the present invention;

FIG. 8 is a fragmentary sectional view of the wiper motor valve casing, taken on line VIII—VIII of FIG. 10 and showing the control valve in its parked position;

FIG. 9 is a fragmentary elevational view of the wiper motor valve casing, partly in section and showing the control valve in its "full on" position;

FIG. 10 is a view taken on line X—X of FIG. 9;

FIG. 11 is a sectional view of the bleed valve;

FIG. 12 is a detailed view of the Bowden cable connections at the control valve;

FIGS. 13 and 14 illustrate additional forms of the invention; and

FIGS. 15 and 16 show the manner in which the coordinator cable is actuated in the modified form of the invention illustrated in FIG. 14.

Referring now to the embodiment illustrated in FIGS. 1, 2 and 3, 1 designates the vehicle windshield, 2 the cowl therebeneath, 3 the instrument panel or shelf interiorly of the vehicle, and 4 the firewall separating the motor compartment from the passenger compartment.

The wiper unit of this system comprises a power unit 5 herein shown as a pneumatic motor, and a wiper 6 carried by an oscillating arm 7 which is mounted on a rock shaft 8 journaled in a suitable housing 9 mounted on the vehicle cowl 2. Motor 5 communicates with a suitable source of suction, such as the intake manifold 10, through a conduit 10'.

Motor 5 is connected to rock shaft 8 by a suitable transmission generally designated 11, and is controlled by a valve 12 slidable on the motor casing and operated by a cable comprising a wire 13 slidably through a casing 14 and connected at one end to valve 12 and at its opposite end to a rack 15. Rack 15 engages a pinion 16, being fitted therewith in a housing 17, and pinion 16 is carried on an actuating shaft 18 having a knob 19 positioned on panel 3 so as to be readily accessible for manual operation by the vehicle operator. A friction spring

21 fits between pinion 16 and housing 17 to resiliently retain pinion 16 in its adjusted position.

Thus, it will be understood that by selectively rotating knob 19 valve 12 will be moved from its parked position illustrated in FIG. 3, wherein the wipers 6 are caused to assume a predetermined position of rest, to its full running position illustrated in FIG. 2 or to any position therebetween to cause a throttled wiper action.

The washer unit illustrated in this embodiment of the invention is more fully disclosed in Patent 2,743,473 issued May 1, 1956, and includes a reservoir 23 for washing fluid and a pump in the form of a bellows 24 mounted on firewall 4 as by a tubular fitting 25 and a lock nut 26. Bellows 24 is adapted to be compressed by a foot operated pedal 27 pivoted on a pin 28 carried by a bracket 29 secured to firewall 4 by fitting 25, and a spring 31 is provided for urging pedal 27 to the position illustrated in FIG. 1 permitting bellows 24 to expand and draw in a charge of fluid from reservoir 23. A conduit 32 extends from fitting 25 to a check valve unit 33 which communicates with reservoir 23 through a conduit 34 and with a discharge nozzle 35, adapted to spray fluid onto windshield 1, through a delivery conduit 36.

Check valve unit 33 is arranged so that when bellows 24 is compressed by depressing pedal 27, the charge of fluid will be discharged therefrom through fitting 25, conduit 32, check valve unit 33 and delivery conduit 36 to nozzle 35, and when pedal 27 is released to permit bellows 24 to expand and resume its normal shape, it will withdraw a charge of fluid from reservoir 23 through conduit 34, check valve unit 33, conduit 32 and fitting 25. As set forth more fully in said copending application, bellows 33 is designed to deliver a predetermined charge of fluid in a relatively fine steady stream, and pedal 27 is fully depressed initially with the resilient bellows side walls distending under hydrostatic pressure and then contracting to cause a steady delivery of a predetermined charge of washing fluid.

Whereas in many conventional prior art systems it would be necessary for the vehicle operator to depress pedal 27 to deliver a charge of fluid to the windshield and to rotate knob 19 to set the wipers in motion, in a system according to this invention the wipers are set in motion automatically upon actuation of the washer, as follows.

A pair of stop posts 40 are provided on the casing of motor 5 in position to abut a stop washer 41 carried by wire 13 when control valve 12 assumes its full running position, as illustrated in FIG. 2. A second cable comprising a wire 42 slideable through a casing 43 interconnects the bellows and the wiper motor, wire 42 being connected at one end thereof to pedal 27 and at its opposite end to a member 44 which is clamped to the adjacent end of casing 14. Casing 43 is secured to bracket 29 and the casing of motor 5 by clamps 45 and 46, respectively.

Upon depressing pedal 27 to compress bellows 24 wire 42 will be pushed into its casing 43 which latter is of sufficient strength to cause wire 42 to slide therethrough and, acting through clamp 44, to swing casing 14 and wire 13 and carry them bodily as a unit to move control valve 12 to its full running position illustrated in FIG. 2. However, casing 43 is designed to have insufficient strength to effect relative movement between wire 13 and its casing 14. There is friction between wire 13 and its casing 14, and in the rack and pinion control, which friction is readily overcome by manual actuation of knob 19 to slide wire 13 through casing 14. Casing 43 is designed so that while it is of sufficient strength to cause wire 42 to slide therethrough and effect movement of casing 14, wire 13 and valve 12 as a unit, it is not sufficiently strong to enable wire 42 to overcome the aforesaid friction such as to cause relative motion between casing 14 and wire 13 once valve 12 is blocked against movement. Instead, upon washer 41 abutting against

posts 40 to preclude further movement of wire 13 in that direction, casing 43 will stretch and open up, so to speak, with the convolutions thereof separating and spreading apart to accommodate any further movement of wire 42 therein by reason of continued movement of pedal 27.

In operation, it will be appreciated that by manually turning knob 19 valve 12 can be moved to any position between parked (FIG. 3) and full running (FIG. 2) for selective wiper operation independently of the washer system.

Now, let it be assumed that the wipers are parked with valve 12 in the position illustrated in FIG. 3, and that it is desired to initiate a windshield washing operation. The vehicle operator simply presses pedal 27 downwardly with his foot and holds the same in that position, bellows 24 being compressed thereby and functioning as previously described to deliver a charge of cleaning fluid in a steady flow through nozzle 35 to window 1. Simultaneously therewith, pedal 27 pushes wire 42 through casing 43 moving wire 13 and casing 14 bodily to the right in FIG. 3 and move valve 12 to its full running position illustrated in FIG. 2. The parts are arranged so that movement of pedal 27 to its fully depressed position will cause movement of valve 12 to its full running position. The washing operation continues until the fluid charge within bellows 24 is depleted or until the vehicle operator releases his foot pressure on pedal 27, and upon releasing pedal 27, spring 31 retracts wire 42 through casing 43 which action moves wire 13 and casing 14 bodily as a unit to retract valve 12 to its parked position illustrated in FIG. 3. Thus, the wiper action is stopped after the washer action, ensuring a thorough wiping of the window.

If wipers 6 are already running at full speed, valve 35 12 having been moved to its position in FIG. 2 by turning knob 19, and it is desired to initiate a washing operation, the following action ensues. As illustrated in FIG. 2, with valve 12 thus moved to its full running position, washer 41 abuts against posts 40, or substantially so, 40 whereby wire 13 and valve 12 are blocked against further movement in this direction. Pedal 27 is depressed to initiate the washing action, causing a measured charge of fluid to be discharged from bellows 24 through nozzle 35 onto window 1, and pushing wire 42 into casing 43. 45 However, since wire 13 and valve 12 are prohibited from further movement by reason of washer 41 engaging against stop posts 40, and since casing 43 is wound with a degree of tightness less than that required to overcome the friction between wire 13 and casing 14 and in the rack and pinion assembly such as to cause relative movement between casing 14 and wire 13, casing 43 opens with the convolutions thereof spreading apart as previously described whereby to accommodate wire 42 as the same is pushed thereto, as illustrated by the broken line showing in FIG. 2. When pedal 27 is released, spring 31 50 simply retracts wire 42 and casing 43 resiliently contracts to its original normal tightly wound condition. In this way, the washing action does not interfere with the preset wiping action, and the wipers continue operating at full speed after the washing operation has stopped and until varied by knob 19.

When valve 12 has been moved by actuation of knob 19 to a position intermediate its parked and full running positions, as illustrated by the broken line showing in FIG. 2, whereby the wipers are running at throttled speed, 65 upon initiating a washing action by depressing pedal 27, wire 42 is pushed into casing 43 which constrains the same to move casing 14 and wire 13 bodily as a unit until valve 12 is moved to its full running position illustrated in FIG. 2 with washer 41 abutting stop posts 40 to stop further movement of valve 12 and wire 13 in this direction. Because of the preset throttled wiping action with valve 12 in an intermediate position when the washer action is initiated, washer 41 will abut posts 40 prior to completion of the pedal stroke. At this point, because

casing 43 is wound with a degree of strength insufficient to constrain wire 42 to cause relative movement between casing 14 and wire 13, the convolutions of casing 43 will expand and spread apart as above described to accommodate the further pushing movement of wire 42 therein. When the pedal 27 is released, spring 31 will pull wire 42 to permit casing 43 to first resiliently contract to its normal condition and wire 42 will then act through clamp 44 to move casing 14 and wire 13 bodily as a unit to retract valve 12. Inasmuch as the first part of the pedal releasing action simply restores casing 43 to its normal condition, the movement of casing 14, wire 13 and valve 12 toward parked position will be only to the extent which they were moved to the full running position, whereby valve 12 will be returned to its preset intermediate or throttled position.

Thus, with an arrangement according to this invention, wherein movement of the motor control valve 12 beyond its full running position is precluded and wherein the washer responsive control valve moving means is designed with sufficient strength to move the wiper control cable and the motor control valve as a unit and insufficient to effect relative movement between the wiper control wire and its casing, full speed operation of the wipers is provided automatically upon actuating the washer unit, and when the washing action is stopped the wipers are automatically restored to the condition of operation for which they were previously set, whether it be parked or throttled. It will be noted that the wiper control cable casing 14 is provided with sufficient curvature between motor 5 and its first point of anchorage on the vehicle to enable free swinging movement thereof as a unit with wire 13 by wire 42 as previously described. If desired, a stop 47 can be provided for abutting against valve 12, in place of the stops 40 engaging washer 41 on the wire 13, as shown in broken lines at 47 in FIGS. 2 and 3.

A window cleaner system according to this invention is also adapted for hydrostatic pressure operation. Thus, FIG. 4 illustrates a system according to the invention wherein the motor 5 and the manually operated wiper control comprising wire 13, casing 14, washer 41, valve 12 and stop posts 40 remain the same, and wherein a piston and cylinder unit actuated by hydrostatic pressure developed in the washer system upon operation thereof is substituted for the pedal controlled cable of FIG. 1. In this embodiment, a cylinder 50 is carried by the motor casing 5, as by brackets 51, and a wall member in the form of a piston 52, mounted on a piston rod 53, is movable therein. Piston rod 53 is clamped to casing 14 by a member 44' for moving casing 14, wire 13 and valve 12 bodily as a unit in the manner above described in connection with the embodiment of FIG. 1 and piston 52 is mounted on rod 53 with a predetermined amount of friction sufficient to move casing 14 and wire 13 as a unit until washer 41 engages against posts 40 but insufficient to overcome the friction in the wiper control and cause relative movement between casing 14 and wire 13. Piston 52 is actuated by hydrostatic pressure on one side thereof caused by fluid delivered under pressure through a conduit 36' which may extend from delivery conduit 36 of FIG. 1, whereby as washing fluid is delivered under pressure from the washer to the windshield a portion thereof is diverted through conduit 36' to one side of piston 52. A retracting spring 54 is arranged on the opposite side of piston 52, which side is open to the atmosphere through a collar 55, and serves to automatically restore the wipers to their original condition of operation after the washing operation whereby to ensure thorough wiping of the window. Piston 52 is provided with a boss 56 which bears against the end wall of cylinder 50 when the piston is fully retracted, and said piston bears against collar 55 when fully extended.

The result achieved by this embodiment is the same as in the embodiment of FIG. 1. Should the wipers be parked when a washing action is initiated, valve 12 being

in the position illustrated in FIG. 4, the washing fluid being discharged creates sufficient pressure against piston 52 to overcome the counter pressure of spring 54 and cause piston 52 and piston rod 53 to move together in a direction causing clamp 44' to carry casing 14 and wire 13 as a unit to move valve 12 to its full running position. Upon cessation of the washing action, the fluid pressure is relieved and piston 52 is restored to the position illustrated in FIG. 4 by spring 54. When the wipers 10 have been preset for full speed operation by knob 19, washer 41 will bear against stop posts 40 to prevent movement of valve 12 beyond its full running position (FIG. 2) and upon initiating a washing action the hydrostatic pressure on piston 52 will cause the same to move along piston rod 53 because the friction therebetween is designed 15 to be less than the friction in the wiper control whereby to avoid relative motion between wire 13 and its casing 14. Thus, the wipers will not be disturbed and upon cessation of the washing action piston 52 will simply be moved in the opposite direction along rod 53 by spring 54. Rod 53 engages against the end wall of cylinder 50 and piston 52 thus will be restored to its retracted position 20 illustrated in FIG. 4 with the wipers continuing to operate at full speed.

Should the wipers have originally been running in a throttled or intermediate speed position with valve 12 positioned between its parked and full running positions, upon initiating a washing action the fluid pressure developed in the system will move piston 52 and rod 53 as a unit and they will act through clamp member 44' to move casing 14 and wire 13 bodily as a unit until valve 12 is moved to its full running position and washer 41 engages stop posts 40. Piston 52 will not yet abut collar 55, and will continue movement in that direction but will now 25 move along rod 53 because valve 12 is stopped from further movement and the friction between piston 52 and rod 53 is not sufficient to overcome the friction in the control cable. Upon cessation of the washing action, spring 54 will move piston 52 and rod 53 in the opposite direction 30 until rod 53 engages the end wall of cylinder 50 at which point valve 12 will be restored to its original throttled position, and because piston rod 53 is positively prevented from further movement in this direction piston 52 will move therealong until its boss 56 abuts the end wall of cylinder 50. Thus, valve 12 is restored to its preset throttled 35 position while the wipers are automatically actuated at full speed during the washing action.

Still another embodiment, utilizing a control valve actuator operated by suction produced pressure differential in response to a washing action is illustrated in FIGS. 5 and 6 wherein parts 5, 12, 13, 14, 40, 41 and 44' are the same as described in connection with the embodiments 40 of FIGS. 1-4. In this embodiment, the washer unit may comprise a reservoir 60 for washing fluid and a pump unit 61 as described more fully, for example, in Patent 2,722,455 issued November 1, 1955. The pump 61 is actuated by suction through a conduit 62 communicating with a conduit 63 extending to a source of suction such as the intake manifold of the vehicle. A control valve 64 which may be adapted for either manual or foot operation 45 is placed in conduit 63 for selectively exposing the pump unit 61 to the source of suction, the pump unit including a spring backed plunger which is retracted by suction influence to take in a charge of washing fluid, and then tripped to relieve the partial vacuum whereby the plunger 50 is driven by its spring to discharge the fluid charge through a delivery conduit 60', as described in said application. A chamber-defining casing 65 carries a movable wall member in the form of a flexible diaphragm 66 therein, and a conduit 67 places one side of diaphragm 66 in communication with the source of suction through conduit 63 controlled by valve 64. This side of the diaphragm is 55 also exposed to the atmosphere through a bleed valve 68 which is adjustable to selectively regulate the same. A rod 69, carried at one end by diaphragm 66, is connected 60 to the plunger of pump unit 61.

at its opposite end to the clamp member 44', and a spring 71 urges diaphragm 66 against the end wall 70 of casing 65 to retract rod 69 thereinto. Spring 71 is designed so that the total operating pressure differential on diaphragm 66 is sufficient to move casing 14 and wire 13 as a unit, but is not sufficient to overcome the friction forces in the wiper control cable such as to cause relative motion therein.

In this embodiment, upon manipulating valve 64 to initiate a washer action, the suction side of diaphragm 66 will be evacuated producing a pressure differential on diaphragm 66 causing movement thereof against the bias of spring 71. Diaphragm 66 pushes rod 69 to carry casing 14 and wire 13 as a unit and move valve 12 to full running position. Upon release of the suction effect, spring 71 will move diaphragm 66 in the opposite direction to retract rod 69 with the speed of this movement being regulated by adjusting bleed valve 68. By proper selection of spring 71 and regulation of valve 68 the wipers can be caused to continue operation for a predetermined period of time after the washing operation if desired. As diaphragm 66 approaches the end wall 70 of casing 65 a projection 72 thereon unseats a valve 73 spring biased to normally close an opening in diaphragm 66. Upon unseating this valve the pressure on opposite sides of the diaphragm will immediately equalize causing a quick final movement of diaphragm 66 under the influence of spring 71 to quickly stop the wiping action.

Should the wipers be set for full or intermediate operation prior to initiating the washer action, this condition is automatically restored after the washing operation. If valve is in full running position with washer 41 bearing against posts 40, upon initiating washer action the pressure differential on diaphragm 66 is not enough to move casing 14 relative to wire 13, whereupon diaphragm 66 will not move and the wipers will remain in full running operation following the washer operation. Should the wipers have originally been set for throttled speed operation, upon initiating a washing action diaphragm 66 will move rod 69, casing 14 and wire 13 only until washer 41 abuts posts 40, at which point movement of diaphragm 66 will stop, and spring 71 will gradually return diaphragm 66 to wall 70 which movement will simply restore control valve 12 to its previously throttled position.

It will be appreciated that if desired the cable of FIGS. 1-3 can be used in the embodiments of FIG. 4 and FIGS. 5 and 6, in which case wire 42 would interconnect piston rods 53 and 69 with casing 14. In such case, piston 52 could be rigidly connected to rod 53, and the piston rods would push wire 42 into its casing 43.

Referring now more particularly to FIGS. 7-16 of the drawings, the motor 5' may be of the conventional variable speed pneumatic type such as that disclosed in Patent No. 2,298,734, October 13, 1942, or one similar thereto, deriving its power from the suction influence of the intake manifold 10 of the vehicle's engine by means of conduit 10'. Control of the motor is attained through the utilization of Bowden cable 13, 14 attached to rack 15 and pinion 16 extending through the instrument panel for manipulation from the passenger compartment of the vehicle. Rotation of the pinion results in movement of control valve 12' from its parked or "off" position shown in FIG. 8 to the "on" position of FIG. 9. When the latter position, air is withdrawn from the pressure chamber of the motor by the intaken manifold of the engine via passageway 111, running valve 120, passageway 130, control valve 12', passageway 140 and conduit 10'. Concurrently, air is forced into the opposite side of the motor through passageway 150 which is exposed to the atmosphere, control valve 12' and passageway 160. A vane, not shown, is as a result forced to move toward the suction or low pressure side of the motor. At the proper time, and in a manner fully described in patent 2,298,734, the running valve is rotated so as to interconnect passageways 130 and 150 while passageway

111 is exposed to the atmosphere. This results in a reversal of air flow, and the vane moves in the opposite direction. The above described cycle continues for so long as control valve 12' remains in the "on" position. Movement of the valve to its "off" position results in the closing of passageways 140 and 150 and the direct connection of passageway 160 to the source of suction via passageway 170 as is clearly illustrated in FIG. 8. The running valve is as a result by-passed and the wipers are held in their parked position.

As is best seen in FIG. 12, one end of the wire of Bowden cable 180 is tied to the armored casing 14 while its opposite end is attached to the spring loaded diaphragm 190. As the resistance of the diaphragm is greater than the internal friction of cable 13, 14, the casing of the latter cable will be held stationary when its wire is moved longitudinally by the rack and pinion to operate valve 12'.

Closure of switch 200 completes an electrical circuit 20 to solenoid valve 210 which opens so as to make available the suction influence of manifold 10 to pneumatically powered pump 220, the air flowing through conduit 230. The pump draws fluid from reservoir 240 and delivers it under pressure to nozzles 35 via conduits 260, 270 and 270'. A jet stream of fluid is as a result directed on to the windshield. For a more detailed description of the operation and construction of the above described washer reference may be made to Patent 2,746,652 issued May 22, 1956.

Simultaneously with the flow of liquid to the nozzles, some of the fluid passes into chamber 280 via conduit 290 and bleed valve 300, the pressure of the fluid lifting plate 310 against the resistance of spring 320 and also deflecting diaphragm 190 to the right against the resistance of spring 330. As one end of the wire 181 of Bowden cable 180 is firmly attached to the diaphragm, the deflection of the latter will result in a longitudinal movement of the wire. Since the opposite end of the wire is attached to the casing 14, said casing will also be urged to move and as the internal friction between the wire 13 and casing 14 is of considerably greater magnitude than the sliding friction occurring between the control valve 12' and surface of the valve casing, the wire and valve will be forced to move with the casing 14. In other words, any deflection of diaphragm 190 will be reflected in a longitudinal movement of control valve 12', cables 180, 181 and 13, 14 being the transmitting media. The dimensions of chamber 280 and its related elements are so designed that the magnitude of the reflected movement of valve 12' is exactly equal to the distance between the "off" and "full on" position of the valve.

It may therefore be seen that the momentary depression of switch 200 will cause pump 220 to deliver a predetermined quantity of fluid to the windshield. Simultaneously and due to the hydrostatic pressure of the fluid, diaphragm 190 deflects so as to move valve 12' from its "off" position, shown in full lines in FIG. 8, to its "full on" position shown in phantom in the same figure. Wipers 6 will as a result commence oscillating and in conjunction with the fluid wash the windshield clean of all sediment and foreign deposits.

After a predetermined quantity of fluid has been delivered to the windshield, pump 220 will, in a manner full described in the above identified Patent 2,746,652, cease operating, and any fluid remaining in the lines will tend to return to reservoir 240. With the drop in hydrostatic pressure plate 310 moves back into contact with its seat under the urging of spring 320, and the fluid returning to the reservoir from chamber 280 is compelled to pass through restricted orifice 340. This results in a delay in return of diaphragm 190 to its normal undeflected position and a continuation of operation of the wipers for several strokes after the cessation of fluid flow so as to insure a clean dry shield at the termination of the washing cycle. When the diaphragm returns to its

undeflected position, it pulls valve 12' back to its "off" position by means of cables 180, 181 and 13, 14 so as to stop the motor and park the blades.

From an inspection of FIGS. 8, 9 and 10 it may be seen that the upper portion of passageway 130 has been enlarged at 43' to an extent which will permit the passageway to remain substantially unrestricted even if valve 12' is moved well beyond its normal "full on" position. If throttle valve 12' is already in its "full on" position as illustrated in full lines in FIG. 9 when the washer is activated, it will nevertheless be moved to the position indicated in phantom in FIG. 9, a distance equal to that between the "off" and "full on" positions since the diaphragm and cables will be moved by the same amount regardless of the position of the valve at the commencement of the washing cycle. However, due to the enlargement of passageway 130, this overtravel of the valve will have no deleterious affect on the motor. The flow of air will remain unrestricted and the motor will continue to operate at full speed. At the termination of the washing cycle the valve will be pulled back to its normal "full on" position by the cables as the diaphragm returns to its undeflected state. It should be obvious that if the wiper motor is being operated in a partially throttled condition, with valve 12' located at some point between the extremes of "off" and "full on," commencement of the washing cycle will cause the motor to operate at top speed with the valve overtravelling its normal "full on" position by an amount equal to the distance between the "off" position and its partially throttled position. At the termination of the washing cycle the valve will be returned to its partially throttled position since as stated above diaphragm 190 will always deflect by the same amount and then return to its normal undeflected position regardless of the location of valve 12' at the commencement of the cycle.

A modified form of the invention is shown in FIG. 13. Herein a manually operated washer is employed in place of the electrically actuated washer of FIG. 7. In this form of the invention a suction bulb or bellows 24 is located on the floor board 420 of the passenger compartment of the vehicle proximate to the head light dimmer switch. Conduit 32 connects the bellows and the washer while foot operated lever 27', pivoted at 28 overlies the bellows. When the operator desires to clear the windshield he depresses lever 27' causing a similar depression of the bellows. Release of the lever causes fluid to be drawn from reservoir 240, past valve 33 into the bellows. When the lever is again depressed the fluid is ejected from the bellows to the nozzles and chamber 280. The remainder of the washing cycle is as described above. For a more detailed description of the washer employed in this form of the invention resort may be had to Patent 2,717,556 issued September 13, 1955.

In the form of the invention disclosed in FIGS. 14, 15 and 16, lever 27" is provided with an integral arm 40 to which the wire of Bowden cable 180' is directly tied. The casing of cable 18' is held stationary by means of collar 45' rigid with the lever mounting plate 29. The opposite end of the wire 181' of cable 180' is tied to the casing 14 in a manner identical to that disclosed above. The ratio of the length of lever 27" to arm 40 is such that a full depression of the lever will cause the arm to swing an amount sufficient to move valve 121 a distance equal to that between its "off" and "full on" positions. As in the previously disclosed forms of the invention, the valve will be moved this distance regardless of its initial position, and will be returned to its initial position at the termination of the washing cycle. It should further be noted that herein a direct mechanical connection exists between the lever and valve with no reliance being placed upon hydrostatic pressure for the control of the motor.

It may therefore be seen that by utilizing the present invention a simple, inexpensive and foolproof system is provided whereby only one manual operation is required to carry out the entire washing cycle. The commence-

ment of fluid application to the windshield, the top speed operation of the wipers, the termination of fluid flow after a predetermined amount of liquid has been delivered, and the subsequent return of the wipers to the exact condition of operation prevailing prior to the commencement of the washing cycle all takes place automatically. The operator need only momentarily close a switch or depress a lever, neither operation requiring the distraction of the operator's attention from the road.

Accordingly, it is seen that the instant invention fully accomplishes the aforesaid objects and provides a highly practical, relatively simple and completely reliable window cleaning system. While certain preferred embodiments have been set forth in detail herein as best illustrating the invention, it is to be understood that the invention is not necessarily limited to the details thereof, and it is intended that this invention be defined by the scope of the appended claims.

Having fully disclosed and completely described this invention, together with its mode of operation, what is claimed as new is:

1. A windshield clearing system for automotive vehicles comprising, a wiper, a variable speed motor for driving said wiper to and fro across an associated windshield, a nozzle for directing a stream of fluid toward the windshield, means for delivering fluid under pressure to said nozzle, a first control means for setting said motor in operation at a desired speed and independently of said fluid delivery means, and a second control means including hydrostatic means responsive to actuation of said fluid delivery means and mechanically tied to said first control means for causing said motor to run at top speed automatically concurrently with operation of said fluid delivery means.
2. A windshield clearing system for automotive vehicles comprising, a wiper, a variable speed motor for driving said wiper to and fro across an associated windshield, a nozzle for directing a stream of fluid toward said windshield, means for delivering the fluid under pressure to said nozzle, a first control means for setting the motor in operation at a desired speed and independently of said pressure means, and a second control means mechanically tied to said first control means and including hydrostatic means for causing said motor to run at top speed concurrently with the actuation of said pressure means, at the termination of the washing operation said second control means returning said motor to the speed of operation prevailing prior to the actuation of said pressure means.
3. A windshield cleaning system for automotive vehicles comprising, a wiper, a variable speed motor for driving said wiper to and fro across an associated windshield, a nozzle for directing a stream of fluid toward the windshield, a reservoir for storage of fluid, means including an operator operated suction bulb operatively connected to said reservoir for delivering fluid under pressure from said reservoir to said nozzle, a manually operable first control means for setting said motor in operation at a desired speed, and a second control means mechanically tied to said first control means and operable automatically to cause said motor to run at top speed whenever said suction bulb is depressed, at the termination of the washing operation said second control means returning said motor to the speed of operation prevailing prior to the depression of said suction bulb.
4. A windshield clearing system for automotive vehicles comprising, a wiper, a variable speed motor for driving said wiper to and fro across an associated windshield, a nozzle for directing a stream of fluid toward said windshield, a reservoir for storage of the fluid, an operator operated suction bulb operatively connected to the reservoir for delivering fluid under pressure from said reservoir to the nozzle, a first control means for setting the motor in operation at a desired speed, a lever for depressing the suction bulb so as to eject the fluid con-

tained therein, a second control means mechanically tied to a portion of said lever for setting the motor in operation at top speed whenever the lever is depressed, upon release of the lever said second control means returning said motor to the speed of operation prevailing prior to the depression of the suction bulb.

5. A windshield clearing system for automotive vehicles comprising, a wiper, a variable speed motor for driving said wiper to and fro across an associated windshield, a nozzle for directing a stream of fluid toward the windshield, a reservoir for storage of fluid, an operator operated suction bulb operatively connected to said reservoir for delivering fluid under pressure from said reservoir to said nozzle, a first control means for setting said motor in operation at a desired speed independently of said fluid delivery means, and a second control means mechanically tied to said first control means and automatically operable to cause said motor to run at top speed concurrently with the delivery of fluid by said suction bulb, a predetermined time after the termination of the washing operation said second control means returning said motor to the speed of operation prevailing prior to such delivery of fluid.

6. A window cleaning system comprising a wiper motor adapted for driving a wiper across a window surface, a motor control valve movable between parked and full running positions, stop means preventing movement of said control valve beyond full running position, first control means comprising a cable and a control member for selectively moving said control valve, said cable comprising a wire movable within a flexible casing and operatively connected at one end to said control valve and at its other end to said control member, a washer unit having means for delivering washing fluid to a window surface, second control means including a second control member for selectively actuating said washer unit, and means responsive to operation of said washer unit for automatically initiating a wiper operation during the washer operation, said last-named means comprising a second cable having a wire movable within a casing, said second wire being operatively connected at its opposite ends to said first cable casing and to said second control member for being pushed by the latter into said second casing, said second casing being of coiled form wound with a sufficient degree of tightness to constrain said second wire to move said first cable and said control valve as a unit while resiliently yielding by spreading apart to accommodate further pushing of said second wire therein after said control valve is in full running position, whereby to prevent relative movement in said first control means, and means for retracting said second wire through its casing to restore said control valve to its position prior to actuation of the washer unit as determined by said first control member.

7. A window cleaning system comprising a wiper motor adapted for driving a wiper across a window surface, a motor control valve movable between parked and full running position, stop means preventing movement of said control valve beyond full running position, first control means comprising a first cable and a first control member for selectively moving said control valve, said first cable comprising a wire movable within a flexible casing and operatively connected at one end to said control valve and at its other end to said first control member, a washer unit having means for delivering washing fluid to a window surface, second control means including a second control member for selectively actuating said washer unit, and means responsive to operation of said washer unit for automatically initiating a wiper operation during the washer operation, said last-named means comprising a second cable having a wire movable within a casing, said second cable wire being operatively connected at one end thereof to said first cable casing and at its opposite end to a movable wall member, means responsive to actuation of said washer unit for creating an operating

pressure on said movable wall member for pushing said second cable wire into its casing, said second cable casing being of coiled form wound with sufficient tightness to cause said second cable wire to effect movement of said first cable as a unit for moving said control valve to full running position while stretching apart as necessary to accommodate further pushing of said second cable wire therein upon said control valve reaching full running position, whereby to avoid producing relative movement in said first control means, and means for retracting said second cable wire to restore said control valve to its position prior to actuation of the washer unit.

8. A vehicle windshield cleaning system comprising a wiper, means including a motor for driving said wiper across the vehicle windshield, a motor control valve slideable on the casing of said motor between parked and full running positions, stop means preventing movement of said control valve beyond full running position, a first control cable comprising a wire slideable within a casing and operatively connected at one end to said control valve, a first control member operatively connected to the other end of said wire for sliding the same within said casing to selectively position said control valve, said first cable being arranged at its end adjacent said motor for movement as a unit, a reservoir for washing fluid, a pump for washing fluid comprising a collapsible bellows member, a discharge nozzle arranged for depositing washing fluid on the vehicle windshield, means including check valve means whereby said bellows member will take in a charge of fluid from said reservoir when expanded and will deliver the same to said discharge nozzle when collapsed, a second control member for collapsing said bellows to selectively initiate a washing operation, and means for initiating a wiper operation automatically upon initiating a washer operation comprising a second control cable having a casing of coiled form and a wire slideable therein, said second cable wire being operatively connected at one end to said first cable casing and at its other end to said second control member for being pushed thereby into said second casing upon movement of said second control member to compress said bellows and initiate a washer operation, said second cable casing being of sufficient strength to cause said second cable wire to move said first cable as a unit and thereby slide said control valve to full running position while being wound with a degree of tightness below that required to produce relative movement in said first cable, the convolutions of said second cable casing spreading apart as necessary to accommodate continued pushing of said second cable wire therein upon said control valve reaching its full running position, and means automatically retracting said second cable wire to subsequently restore said control valve to its original position as determined by said first control member.

9. A window cleaning system comprising, in combination, a wiper unit having a wiper and means including a motor for driving said wiper, motor control means movable between full on and off positions, first actuating means for moving said control means between on and off positions to selectively actuate said wiper unit, a washer unit having means for delivering washing fluid to a window in the path of said wiper, second actuating means for selectively actuating said washer unit, said first actuating means being operable independently of said second actuating means, and means responsive to actuation of said washer unit by said second actuating means for moving said control means to full on position thereby automatically securing full speed wiper operation during the washer operation and for subsequently restoring said control means to its original position as determined by said first actuating means, said last-named means including a resiliently expandable casing and a wire therein operatively connected to said control means, said wire being pushed through said casing to move said control means to full on position upon actuation of said washer

unit and said casing resiliently expanding to accommodate further pushing of said wire therein when said control means is in full on position.

10. A window cleaning system comprising a wiper motor adapted for driving a wiper across a window surface, a motor control valve slideable on the motor casing between parked and full running positions, first stop means carried by said motor casing, first control means comprising a cable and a control member for selectively moving said control valve, said cable comprising a wire movable within a flexible casing and operatively connected at one end to said control valve and at its other end to said control member, second stop means carried by said wire for abutting said first stop means to prevent movement of said control valve beyond full running position, a washer unit having means for delivering washing fluid to a window surface, second control means for selectively actuating said washer unit, and means responsive to operation of said washer unit for automatically initiating wiper operation during washer operation, said last-named means being operatively connected to said cable casing and operable to move said cable bodily as a unit for moving said control valve from its position as determined by said first control member to full running position and then back again while being inoperable to overcome the friction in said first control means and cause relative movement therein.

11. A window cleaning system comprising a wiper motor adapted for driving a wiper across a window surface, a motor control valve movable between parked and full running positions, stop means preventing movement of said control valve beyond full running position, first control means comprising a cable and a control member for selectively moving said control valve, said cable comprising a wire movable within a flexible casing and operatively connected at one end to said control valve and at its other end to said control member, a washer unit having means for delivering washing fluid to a window surface, second control means for selectively actuating said washer unit, and means responsive to operation of said washer unit for automatically initiating wiper operation during washer operation, said last-named means being operable to move said cable bodily as a unit for moving said control valve from its position as determined by said first control member to full running position and then back again and comprising a rod clamped adjacent one end thereof to said cable casing, a movable wall member operatively connected to said rod adjacent the opposite end thereof for moving the same, means for producing a fluid pressure differential on said wall member in response to operation of said washer unit for moving said wall member in one direction to push said rod and move said control valve to full running position, and spring means biasing said wall member for return movement in the opposite direction, said spring means being designed to provide in conjunction with said pressure differential a total operating pressure against said wall member sufficient to move said cable and said control bodily as a unit while being less than that required to produce relative movement in said cable, together with adjustable bleed means for relatively slowly relieving the fluid pressure differential on said wall member, and valve means operable upon predetermined return movement of said wall member by the action of said spring means to quickly equalize the fluid pressure on opposite sides of said wall member.

12. A windshield clearing system for automotive vehicles comprising, a variable speed fluid operated motor having a plurality of fluid passageways opening through a valve seat, a control valve slideable on said seat, the cross-section of a portion of at least one of said passageways adjacent said valve seat being larger than the cross-sections of said other passageways to enable overtravel of said control valve beyond its full on position relative to said valve seat substantially without restricting said one passageway, a wiper operatively connected to said motor so as to be driven to and fro across an associated wind-

shield by said motor, a nozzle for directing a stream of fluid toward the windshield, means for delivering fluid under pressure to said nozzle, a first control means operatively connected to said control valve for moving the same relative to said seat to set said motor in operation at a desired speed independently of said fluid delivery means, and a second control means responsive to actuation of said fluid delivery means and mechanically tied to said first control means for causing the same to move said control valve relative to said seat to cause said motor to run at top speed automatically concurrently with the actuation of said fluid delivery means.

13. A windshield clearing system for automotive vehicles comprising, a variable speed fluid operated motor having a plurality of fluid passageways opening through a valve seat, a control valve movable on said seat, the cross-section of the seat portion of at least one of said passageways being larger than the cross-sections of said other passageways, a wiper operatively connected to said motor so as to be driven to and fro across an associated windshield by said motor, a nozzle for directing a stream of fluid toward said windshield, means for delivering the fluid under pressure to said nozzle, a first control means for moving said valve on said seat to set the motor in operation at a desired speed and independently of said pressure means, and a second control means operatively connected to said first control means and including hydrostatic means for moving said valve on said seat to cause said motor to run at top speed concurrently with the actuation of said pressure means, at the termination of the washing operation said second control means returning said motor to the speed of operations prevailing prior to the actuation of said pressure means, said larger passageway portion enabling overtravel of said valve on said seat substantially without restricting said one passageway.

14. A windshield clearing system for automotive vehicles comprising, a variable speed fluid operated motor having a plurality of fluid passageways opening through a valve seat, a control valve movable on said seat, the cross-section of the seat portion of at least one of said passageways being larger than the cross-sections of said other passageways, a wiper operatively connected to said motor so as to be driven to and fro across an associated windshield by said motor, a nozzle for directing a stream of fluid toward the windshield, a reservoir for storage of fluid, an operator operated suction bulb operatively connected to said reservoir for delivering fluid under pressure from said reservoir to said nozzle, a first manually operable control means for moving said valve on said seat to set said motor in operation at a desired speed, and a second control means mechanically tied to said first control means for causing the same to move said valve on said seat to cause said motor to run at top speed whenever said suction bulb is depressed, at the termination of the washing operation said second control means returning said motor to its speed of operation prevailing prior to the depression of said suction bulb, said larger passageway portion enabling overtravel of said valve on said seat substantially without restriction of said one passageway.

15. A windshield clearing system for automotive vehicles comprising, a variable speed fluid operated motor having a plurality of fluid passageways opening through a valve seat, a control valve movable on said seat, the cross-section of the seat portion of at least one of said passageways being larger than the cross-sections of said other passageways, a wiper operatively connected to said motor so as to be driven to and fro across an associated windshield by said motor, a nozzle for directing a stream of fluid toward the windshield, a reservoir for storage of fluid, means including an operator operated suction bulb operatively connected to said reservoir for delivering fluid under pressure from said reservoir to said nozzle, a first control means operatively connected to said control valve for moving the same on said seat and thereby setting said motor in operation at a desired speed, a lever for depressing said suction bulb so as to eject the fluid contained

therein, a second control means mechanically tied to a portion of said lever and to said first control means for moving said valve on said seat and thereby setting said motor in operation at top speed whenever said lever is depressed, upon release of said lever said second control means returning said motor to its speed of operation prevailing prior to the depression of said suction bulb, said larger passageway portion enabling overtravel of said valve on said seat substantially without restriction of said one passageway.

16. A windshield clearing system for automotive vehicles comprising, a variable speed fluid operated motor having a plurality of fluid passageways opening through a valve seat, a control valve movable on said seat, the cross-section of the seat portion of at least one of said passageways being larger than the cross-sections of said other passageways, a wiper operatively connected to said motor so as to be driven to and fro across an associated windshield by said motor, a nozzle for directing a stream of fluid toward the windshield, electrically actuated means for delivering the fluid under pressure to the nozzle, and control means including hydrostatic means for moving said valve on said seat and thereby setting the motor in operation at top speed when said pressure means commences to deliver fluid, a predetermined time after the termination of the washing operation said control means returning said motor to the speed of operation prevailing prior to the delivery of fluid by said pressure means said larger passageway portion enabling overtravel of said valve on said seat substantially without restriction of said one passageway.

17. A windshield clearing system for automotive vehicles comprising, a variable speed fluid operated motor having a plurality of fluid passageways opening through a

valve seat, a control valve movable on said seat, the cross-section of the seat portion of at least one of said passageways being larger than the cross-sections of said other passageways, a wiper operatively connected to said motor so as to be driven to and fro across an associated windshield by said motor, a nozzle for directing a stream of fluid toward the windshield, a reservoir for storage of fluid, means including an operator operated suction bulb operatively connected to said reservoir for delivering fluid under pressure from said reservoir to said nozzle, a first control means operatively connected to said control valve for moving the same on said seat and thereby setting said motor in operation at a desired speed, and a second control means responsive to operation of said suction bulb for moving said valve on said seat and thereby causing said motor to run at top speed automatically concurrently with the delivery of fluid by said suction bulb, a predetermined time after the termination of the washing cycle said second control means returning said motor to its speed of operation prevailing prior to the delivery of fluid said larger passageway portion enabling overtravel of said valve on said seat substantially without restriction of said one passageway.
